GAME APPARATUS

Isaac H. Athey, Chicago, Ill.

Application August 20, 1938, Serial No. 225,840

4 Claims. (Cl. 273—40)

My invention relates to game apparatus and more particularly to game apparatus which may be equally well utilized indoors or outdoors and which has a wide appeal because the game to be 5 played therewith is one of skill.

Bowling is a game of wide appeal that is of limited availability because of the initial cost of equipment and because of space requirements. It is not a "parlor" game, although attempts have 10 been made to make it such by provision of miniature sets of balls and pins. Miniature sets, however, have certain disadvantages that detract considerably from the enjoyment to be derived from their use. It is a primary purpose of my invention 15 to provide a game apparatus which, while it is somewhat similar to bowling, has been modified somewhat to render it readily installable in homes and amusement places in general without, however, detracting either from the skill necessary to play the game or from the enjoyment of 20 the players.

It is an object of my invention to provide a game apparatus comprising a set of bowling pins and a suspended ball which may be thrown at the 25 pins by the player. The pins are set up relatively near each other and in a predetermined form, preferably a triangle having its apex toward the bowler. There are four pins ordinarily in the rear or fourth row, three in the third row, two in 30 the following, and one in the row nearest the player. The suspended ball is adapted to be thrown against the pins and, in order to knock down most pins, it is necessary, just as in bowling, that the ball hit the pocket between the head 35 pin and either of the two pins in the adjoining row.

An object of my invention is so to arrange the ball suspension with respect to the pins that the ball will not bounce over the remaining pins after 40 it strikes one as it is thrown towards the balls from a position in front thereof.

A more specific object of my invention is so to arrange the ball suspension with respect to the pins that all the pins are adapted to be struck 45 at points somewhat below the maximum diameter portion of either the heads or the main body portions of the pins, thereby to prevent the ball from bouncing upward as it glances off of a pin.

A further object of my invention is to provide 50 the game apparatus with a combined baffle and ball retainer so arranged with respect to the ball suspension as to prevent the ball from endangering anyone near the game apparatus and at the same time prevent the ball from knocking down 55 pins on a rebound.

A further and more specific object of my invention is to obtain the desired relationship between the pins and the ball by mounting the pins upon a generally triangular plate at different elevations so that they occupy positions on a line 5 that is arcuate in the direction of travel of the ball.

Another more specific object of my invention is slidably to suspend the ball from a generally downwardly and rearwardly extending support so 10 that the ball is adapted to move not only forwardly but also downwardly as it strikes the baffle, whereby the ball is caught in a ball retainer located below the baffle when it moves downwardly under the force of gravity.

Other objects and advantages of my invention will become apparent from the ensuing description, in the course of which reference is had to the accompanying drawings, in which:

Fig. 1 is a perspective view of the game apparatus of my invention illustrating the manner in which the ball is held by the player preparatory to its being thrown toward the pins;

Fig. 2 is a perspective view of a modified form of the game apparatus illustrating in particular 25 the fact that the apparatus may be made in various sizes and for installation in various locales;

Fig. 3 is a vertical longitudinal sectional view taken along the line 3—3 of Fig. 1;

Fig. 4 is a horizontal sectional view taken along 30 the line 4—4 of Fig. 1, with the pins removed better to illustrate the top of the novel pin supporting plate of my apparatus; and

Fig. 5 is a view similar to Fig. 3 of a further modification of my invention in which the ball is 35 adapted to strike the pins below the maximum diameter portions of the bodies of the pins rather than the heads as in the previously illustrated modifications.

Referring now to the drawings, it may be noted 40 that the apparatus comprises a horizontally disposed open-top tray indicated by the reference numeral 10, an upwardly extending open-front cabinet structure 12 located at the rear end of the tray, a rigid supporting post 14 extending upward and slightly forward from the cabinet structure, and a ball 15 flexibly suspended from the post in a manner to be described fully herein-after.

In the modification illustrated in Figs. 1, 3 and 50 4, the tray 10 is supported at its front end upon a single hinged leg 16 located substantially centrally of the table and at its rear end upon a pair of hinged legs 18 hinged to the under side of the tray. The tray support is made relatively rigid 55

by suitable braces indicated by reference characters 20 and 22 and further rigidity is obtained by means of cross pieces 24 and 26 bearing against the bottom of the tray and attached to the legs 5 for movement therewith, as best illustrated in Fig. 1.

The tray comprises a base 28 and side walls 30 which may be suitably finished in order to give the structure a pleasant appearance and which 10 are of a height to prevent the pins 31 supported therein from falling to the floor as they are knocked down.

The cabinet is constructed of a pair of identical side panels 32, a rear panel 34, and a relatively 15 narrow apertured top 36 through which the ball supporting post 14 enters. The post which is preferably made of a square piece of substantially rigid material, such as wood, is securely held in place by the apertured top 36 and a suitable re- 20 ceptacle 38 fastened to the tray base 28.

A combined baffle and ball retainer that forms an important feature of my invention and the functioning of which will be described in greater detail hereinafter, is supported from the side 25 panels and top of the cabinet. The combined baffle and ball retainer comprises a relatively heavy, but flexible, fabric curtain-like piece 40 secured at its upper end to the top 36 by a fastening strip 42. At its opposite end the baffle 30 is secured to a cross bar 44 extending between and attached to the side panels 32 by looping it around the bar, as clearly indicated in Fig. 3. The length of the baffle is greater than the straight line distance between the upper front 35 edge of the cabinet and the cross bar so as to define a pocket located below the baffle and the normal position of the ball for receiving the ball, the pocket being indicated by reference numeral 46.

40 In the embodiment of the invention illustrated in the drawings, the baffle has been illustrated as being made of single ply material somewhat similar to material used in making awnings. This construction may be modified as the only 45 prerequisite of the material is that it be flexible in order that the ball will not bounce back toward the thrower upon striking the baffle. It follows therefore that the baffle may be made of multi-ply material and the material need not be 50 a textile fabric.

Another salient feature of my invention is so to support the ball 15 that is held in the ball retaining pocket 46 after each throw. The arrangement for accomplishing this comprises 55 mounting the ball at the end of a flexible support 52, preferably a light weight metal chain, which is, in turn, slidably mounted upon a support 54 extending forwardly and upwardly from the upper end of post 14. The support is a rod- 60 like member made of a relatively heavy piece of metallic tubing such as, for instance, $\frac{3}{4}$ inch pipe upon which the flexible chain is slidably mounted by a ring 56 having an internal diameter slightly greater than the external diameter of the pipe. To prevent the ball from sliding off the forward end, the support terminates 65 in a knob 58 and to enable the ball readily to be brought back to its initial position, wherein it is indicated in solid lines in Fig. 1, a spherical ball 70 60 is interposed between the post and support. This ball provides a relatively wide surface against which the ring rests at one extreme of its movement and from whence the chain can be returned to the front end of the support with 75 ease. The sliding support 54 is so configured that

the ring 56 starts to slide toward the post when the ball reaches a position immediately in front of or just as it strikes the baffle. Consequently, when the ball strikes the baffle, its forward movement is terminated and it is actuated downwardly by the force of gravity. Since support 54 5 slopes downwardly toward the upper end of the post, the ball and chain are both free to move downwardly. In order to prevent the ball from moving downwardly as soon as it is thrown, the forward end of the support 54 is made with a substantially horizontal portion indicated by reference numeral 62. The intermediate portion of the support, indicated by reference numeral 64, slopes downwardly at an angle of about 15 degrees whereas the rear portion, indicated by reference numeral 66, slopes downwardly at an angle of about 30 degrees. Thus, as the ball starts to move downwardly after striking the baffle, the portions 64 and 66 permit the ball to 20 fall into the pocket 46 at an increasing rate.

The support 54 extends forward from the post 14 at a distance such that when the ball is freely suspended it lies substantially centrally of the pins in a transverse direction and intermediate 25 the second and third rows, counting the rows from the front. This position of the ball is indicated in Figs. 2 and 3.

Another essential feature of my invention resides in so arranging the pins 31 that the ball is 30 adapted to strike each pin slightly below the maximum diameter portion of the head, as illustrated particularly in Fig. 1 or below the maximum diameter portion of the body of the pin as will be described more fully hereinafter in connection with the modification of Fig. 5, thereby 35 to prevent the ball from bouncing over some pins after striking one. This feature is provided by a pin plate 70 preferably, but not necessarily, made of a number of similar sections of wood 40 superposed upon one another with portions thereof in vertical alignment in such manner as to provide shoulders at different elevations upon which the pins may be mounted. The similar sections are preferably triangular in form and 45 have their apex defining portions in vertical alignment. More specifically, the pin plate comprises a generally triangular bottom portion 72, a somewhat shorter triangular portion 74 superposed thereon, a similar and smaller portion 76 50 superposed on portion 74, and a further similar and smaller portion 78 superposed on portion 76. The pin plate is completed by a positioning portion 80 placed at the forward end of portion 78. The ready positioning of the pins is provided by semi-circular cut-out portions 82 at the rear end of portions 74 to 80, inclusive, as is 55 clearly apparent from Fig. 4.

From the preceding detailed description it is 60 apparent the pin plate provides a set-up of the pins that is arcuate in the direction of travel of the ball and that the ball will strike all the pins in a limited portion of their length, i. e., where the pin recedes downwardly and centrally. The 65 various positions of the ball as it strikes the pins is thus illustrated in Fig. 3, where the ball has been indicated in phantom at various positions.

The game apparatus described above may be supported not only upon an associated support, 70 but also upon a table as illustrated in Fig. 2. In this modification the legs have been omitted and the tray 10 has been illustrated as supported upon a table 84. In this modification only six pins have been illustrated, thus illustrating the 75

fact that my invention is susceptible of modification.

In both modifications the supporting post 14 has been illustrated as slanting forward. This construction enables a shorter piece of tubing to be used for the support 54. If the support 54 is made too long, it is liable to bend when the player grasps the ball 15 and bending of the support is likely to cause the ball 15 to spring upwardly when it is released. This would be a decided disadvantage as it would cause the ball to strike the pins an upward glancing blow. This in turn would cause the ball to bounce over some of the pins. Some caution should be exercised in determination of the size of the ball. The ball should not be too large as the game would be made too easy. I have found that a ball of the size of an ordinary baseball gives good results with pins having a height of about eight inches. However, the ball may be made larger to make the game easier and smaller to make it more difficult.

The modification of my invention illustrated in Fig. 5 is similar to that illustrated in Figs. 1, 25 3 and 4, differing from the latter primarily in the arrangement of the support for the ball 15, whereby the latter is adapted to strike the main body portions of the pins in a downwardly and centrally receding region. An advantage of this arrangement is that it permits the use of a heavier ball and makes the game even more similar to regulation bowling.

Similar reference characters have been utilized to indicate parts that are practically the same as those in the modification illustrated in Figs. 1, 3 and 4. Referring now more particularly to Fig. 5, it may be seen that the supporting tray 28 has been lengthened somewhat and that it has been provided with side walls 84 (only one of which is shown) extending upwardly and rearwardly from the front wall 85 of the cabinet to the top panel 36. The purpose of this side wall, which may be incorporated in the previously described modifications, is to prevent the ball 45 from swinging sideways after it strikes the pins. It also performs the additional function of preventing the pins from falling off the horizontal support.

Another advantage of the modification now being described, is that the ball retaining pocket may be made much smaller or eliminated entirely if desired. However, it is preferable to provide the device with a small ball retaining pocket. The baffle 86 is made of the same material as the baffle 40 of the previously described modifications and is secured at its upper end to the top by a fastening strip 42. At its lower end the baffle is secured to a crossbar 88 extending between and attached to the side panels 84 by looping it around the bar as clearly indicated in the figure. The length of the baffle is slightly greater than the straight line distance between the upper front edge of the cabinet and the crossbar so as to define a pocket located below the baffle and the normal position of the ball for receiving the latter, the pocket in this case being indicated by reference numeral 90. It may be seen from the figure that the crossbar 88 is located relatively near to the horizontal support 28 in order that the ball may first strike the baffle 86 and thereafter drop into the pocket 90.

The pin plate indicated in this modification by reference numeral 92 is substantially the same in construction as the previously described pin plate 10 with exception of the fact that the front

end has been made somewhat longer as indicated by reference numeral 94. The reason for this is to provide a construction whereby the ball is adapted to move past the front wall 85 without striking it.

In utilizing the apparatus of my invention, the ball is first grasped and brought into substantially the position shown in solid lines in Fig. 1. The player then throws it with some force toward the pins. The idea is, just as in bowling, to strike the pins in the pockets formed by the head pin and either of the two pins in the second row. When the ball strikes the first pin, it is deflected somewhat and it strikes the second row and from there it goes past the succeeding rows. By arranging the ball so that it is located substantially in the position shown in Fig. 3 when freely suspended and by arranging the pins upon a pin plate such as that described above, all of the pins are adapted to be struck slightly below the maximum diameter portion of the head, and the ball is prevented from bouncing upwardly when it strikes any particular pin. Consequently, the ball moves through the successive rows of pins just as would a ball that is rolled down an alley. After the ball has passed the last row of pins, it moves toward the baffle and when it reaches a position very near the baffle or strikes the baffle, the sliding connection of the chain permits the ball to slide away from the front end of the support 54. When the ball strikes the baffle, its forward movement is terminated and the sliding connection permits the ball to drop into the pocket 46 formed by the baffle. The combined baffle and ball retainer thus prevent the ball from rebounding toward the pins after it has passed the last row.

The apparatus of the modification illustrated in Fig. 5 is adapted to be utilized in substantially the same way as that just described. The only difference between it and the other is that the ball is positioned below the maximum diameter portions of the bodies of the pins when freely suspended, so that when the ball is thrown at the pins, it strikes them slightly below the maximum diameter portion of the body. It may be seen therefore that the principles involved are identical in the two modifications of ball and pin arrangements.

It should be apparent that the baffle and the ball support may be made of materials other than those specifically described herein and that the particular forms and shapes thereof may be modified without departing from the spirit of my invention.

Furthermore, it should be apparent that certain of the features of my invention may be utilized independently of the others; for example, the combined baffle and ball retainer may be used with pins of various types and not alone with the pins of the shape illustrated and described herein.

What I claim as new and desire to secure by Letters Patent is:

1. Game apparatus including in combination a platform, a plurality of pins adapted to be set up on said platform, a ball flexibly supported above the platform in such manner that it may be thrown at and is adapted to strike the pins set up on the platform, a baffle located behind the platform and against which the ball is adapted to strike after passing beyond the pins thereon, a ball retaining pocket interposed between the baffle and platform, and a ball support comprising a generally inclined track above the platform 75

and pocket and having a sharp drop over the pocket whereby the ball drops into the pocket and is prevented by the forward edge of the pocket from rebounding against pins remaining on the platform.

2. Game apparatus including in combination a platform, a plurality of pins adapted to be set up on said platform, said pins having portions receding downwardly and centrally thereof, a ball 10 flexibly supported above the platform in such manner that it may be thrown at and is adapted to strike the pins set up on the platform, said platform being constructed to support the pins at different elevations corresponding approximately to the line of travel taken by the ball as it is thrown at the pins, a baffle located behind the platform and against which the ball is adapted to strike after passing beyond the pins thereon, a ball retaining pocket interposed between the baffle and platform, a ball support comprising a generally inclined track above the platform and pocket and having a sharp drop over the pocket whereby the ball drops into the pocket and is prevented by the forward edge of the pocket from rebounding against pins remaining on the platform, and a flexible connection between the track and ball of such length that the ball is adapted to strike each pin at said downwardly and centrally receding portion.

3. Game apparatus including in combination a platform, a plurality of pins adapted to be set up on said platform, said platform comprising a plurality of thicknesses of material of different areas and similar shape attached together with portions thereof substantially in vertical alignment whereby there are provided a plurality of

areas of different thicknesses to form a unitary structure, said structures being provided with cut-away portions along portions of their non-aligned edges to receive and position the pins, a ball flexibly supported above the platform in such manner that it may be thrown at and is adapted to strike the pins set up on the platform, a baffle located behind the platform and against which the ball is adapted to strike after passing beyond the pins thereon, a ball retaining pocket interposed between the baffle and platform, and a ball support comprising a generally inclined track above the platform and pocket and having a sharp drop over the pocket whereby the ball drops into the pocket and is prevented by the forward edge 15 of the pocket from rebounding against pins remaining on the platform.

4. Game apparatus including in combination a platform, a plurality of pins adapted to be set up on said platform, a ball flexibly supported above the platform in such manner that it may be thrown at and is adapted to strike the pins set up on the platform, a baffle located behind the platform and against which the ball is adapted to strike after passing beyond the pins thereon, 20 a ball retaining pocket interposed between the baffle and platform, said baffle and pocket being formed by a single flexible transverse curtain, and a ball support comprising a generally inclined track above the platform and pocket and having a sharp drop over the pocket whereby the ball drops into the pocket and is prevented by the forward edge of the pocket from rebounding against pins remaining on the platform.

ISAAC H. ATHEY.
